UNITED STATES PATENT OFFICE.

FRANK MARTIN, OF WORCESTER, MASSACHUSETTS, ASSIGNOR TO WRIGHT WIRE COMPANY, OF WORCESTER, MASSACHUSETTS, A CORPORATION OF MASSACHUSETTS.

FISH-FLAKE.

1,121,853.

Specification of Letters Patent. Patented Dec. 22, 1914.

Application filed October 4, 1912. Serial No. 723,844.

To all whom it may concern:

Be it known that I, FRANK MARTIN, a citizen of the United States, residing at Worcester, in the county of Worcester and 5 Commonwealth of Massachusetts, have invented a new and useful Improvement in Fish-Flakes, of which the following, together with the accompanying drawing, is a specification.

10 My invention relates to fish flakes for supporting fish or the like while it is being dried or otherwise treated.

An object of the invention is to provide a flake with peculiarly reinforced edges so 15 that the flake will outwear any as previously constructed and be adapted to continue in service for a long period of time.

Further objects and advantages will appear from the following description taken 20 in connection with the accompanying drawing, in which—

Figure 1 shows a flake constructed in accordance with my invention, portions of the reinforcements along the edges thereof being broken away to show details of construction, and Fig. 2 is a cross sectional view of 25 one of the reinforced edges of the flake.

Similar reference characters indicate like parts in both figures.

30 The main or body portion 1 of the flake consists of a substantially flat and preferably rectangular piece of wire screen through which heated air, smoke and the like may readily pass. Unless this screen is 35 strongly reinforced, it is sure to be badly bent and damaged while in use and to overcome this difficulty I provide each edge of the screen with suitable reinforcement.

The reinforcement for each edge of the 40 flake includes a binding strip 2 of galvanized iron, or other suitable material, bent around the edge of the screen 1 so as to extend over both faces of the screen a short distance. A very efficient additional reinforcement is also provided in the shape of a stout metallic rod 3 laid along the edge of 45 the screen 1 and within the binding strip 2.

The parts of the flake are secured together by rivets 4 passed through the binding strips

2 and the screen 1. The binding strips overlap at the corners so that each rivet passes through two binding strips, the whole being thus securely fastened together. The rods 3 are short enough so as not to extend close to the rivets 4 and cause undue thickness or bunching at the corners of the flake where the binding strips 2 overlap. The edges of the flake are further strengthened and the parts more firmly secured together by forming a corrugation longitudinally of 50 each binding strip so that the binding strips will grip firmly the edges of the screen and will be also greatly stiffened.

Having described my invention, what I claim as new and desire to secure by Letters 55 Patent is:

1. A fish flake, comprising a sheet of foraminous material, a binding strip for each edge of said sheet, each strip being folded upon itself to inclose the said edge, 70 and extending into overlapping relation at its ends with the ends of the binding strips of adjacent edges, and a stiffening member disposed within the fold of each binding strip, longitudinally of the inclosed edge, 75 and terminating short of the overlapping end portions of said strip.

2. A fish flake, comprising a sheet of foraminous material, a binding strip for each edge of said sheet, each strip being 80 folded upon itself to inclose the said edge, and crimped longitudinally inwardly of said fold, with the ends of each strip disposed in overlapping relation to the ends of strips of adjacent edges, a stiffening member disposed within the fold of each strip and outside the crimp thereof, each of said members lying wholly within and between the overlapping end portions of its strip, and means, beyond the ends of said members, 85 for securing the overlapping portions of said binding strips together.

Dated this second day of October 1912.

FRANK MARTIN.
